(57) **CLAIM**

The ornamental design for a gateway, as shown and described.

DESCRIPTION

FIG. 1 is a front perspective view of a gateway showing our new design;

FIG. 2 is another front perspective view thereof;

FIG. 3 is a rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken lines depicting the remainder of the gateway, and the circular elements on the top surface of the gateway, show features that form no part of the claimed design.
